UNITED STATES PATENT OFFICE.

PAUL J. CUBBISON, OF NEW CASTLE, PENNSYLVANIA.

AUTOMOBILE-HEATER.

1,306,581.

Specification of Letters Patent. Patented June 10, 1919.

Application filed April 4, 1917. Serial No. 159,774.

To all whom it may concern:

Be it known that I, PAUL J. CUBBISON, a citizen of the United States, and resident of New Castle, in the county of Lawrence and State of Pennsylvania, have invented 5 a new and useful Improvement in Automobile-Heaters; and I do hereby declare the following to be a full, clear, and exact description thereof.

10 This invention relates to heating appliances and is particularly, though not exclusively, concerned with heaters for automobiles. One of the great difficulties in such heaters is that the passage for the 15 gases through the heating element is usually of larger cross-section than that of the intake, and also sometimes the diameter of the intake pipe is larger than that of the engine exhaust pipe from which the gases are taken. This results in expansion of the 20 gases before reaching the heater, which absorbs the heat, thus lowering the heating efficiency of the heater; also, if too small a tubing be used to supply the gases from 25 the exhaust pipe to the heating element, the result is a large loss of heat units and a shrinkage of the gases before they reach the heating element through radiation which lowers the heating efficiency.

30 One of the objects of this invention is, therefore, to provide a construction in which the passage through the heating element is of uniform diameter, so that there will be no expansion of the gases in their passage 35 through the heater resulting in loss of radiant heat.

A further object is to supply the gases 40 through a tube of larger cross-sectional area than the cross-sectional passage through the heating element thus supplying the gas with the maximum amount of heat to the heating element thus raising the efficiency of the heater.

45 A further difficulty with these heaters results from the noise produced from the exhaust of the gases from the heating element. This invention overcomes this difficulty by giving the gases a whirling motion at the heater outlet, whereby the noise 50 of the escaping gases is silenced. With this and other objects in view, as will appear from the following description, the invention consists in the construction and arrangement of heating device, preferred em-

bodiments of which are illustrated in the 55 accompanying drawings, though it is to be understood that the invention is not limited to the precise forms here illustrated and described.

In the drawings, Figure 1 shows a plan 60 view of one form of heater element; Fig. 2 is a horizontal sectional view of the device shown in Fig. 1; Fig. 3 is a vertical sectional view on the line 3—3, Fig. 1; Fig. 4 is a cross-sectional view on the line 4—4, 65 Fig. 1; Fig. 5 is a vertical section of a different arrangement of the heater; and Fig. 6 is a fragmentary vertical longitudinal section of the form of heater shown in Fig. 5.

In the embodiment of my invention herein selected for illustration, and as illustrated in Figs. 1 to 4 inclusive, 1 indicates the 70 heater element proper which may be in the form of a casting having passages 2, 3 and 4 separated by baffle-walls or baffle-plates 75 5 and 6. The inlet opening is illustrated at 7 and communicates by a lateral passage 8 with the first heater passage 2. The heater passage 2 communicates with the heater passage 3 by means of an opening 9 at the end of the heater opposite the inlet, and passage 3 communicates with passage 4 by means of an opening 10 adjacent the inlet, but separated therefrom by a wall 11. The passage 4 communicates with an 80 outlet opening 12 through a lateral passage 13 in the wall 14 of the outlet. It will be noted that the gases in entering the heater 85 impinge against a curved wall 15 near the inlet end. This gives the gas more or less of a whirling motion in the heater passage and this whirling motion continues in the 90 gas as it passes along the passages 2, 3 and 4. In order that the gases may not be pocketed 95 in the end space 16 of the heater, I provide the wall 11 of the inlet opening with an aperture 17, whereby the incoming gases being under greater pressure due to carrying a greater number of heat units not having contracted through radiation of heat, 100 such as the gases in passage 4, a portion of the gases pass through apertures 17 under pressure, causing a jet of the incoming gas to pass directly into passage 4 causing the gases in passage 4 to have a greater velocity, 105 also preventing pocketing of dead gases in space 16. As the gas passes out from the heater passage 4 through the outlet opening 13 into

the outlet 12, it is again given a further whirling motion by reason of impingement against the wall 18 adjacent the outlet opening. Moreover, this whirling motion is accentuated or increased by forming a passage 19 in the wall 14 of the outlet opening which passage 19 is arranged tangentially to the outlet and serves to increase the whirling motion of the gas, so that when the latter 5 escapes from the heater, such whirling motion will serve to silence the noise of the exhaust. The heater element beneath the floor of the car may of course be surrounded by the usual sheet metal jacket 20 upon which 10 the grille 21 is mounted forming the floor protection over the heating element. The sheet metal casing may, if desired, be provided with struck-down portions 22 which, as shown in Fig. 4, may be directed toward 15 the front of the car in order to admit fresh air to the casing to be heated by the heater element.

In the form of the invention illustrated in Figs. 5 and 6, the heater element 23 may 25 be arranged in upright position having a flange base 24 and the passages 25, 26 and 27, such passages communicating with each other in a manner similar to that heretofore described, as for example, an opening 28 30 affording communication between adjacent passages.

It is to be noted that this heating element is cast in one piece, therefore, there are no parts to be assembled other than the connecting up of the inlet and outlet pipes. Furthermore, the heater element is cast in such form that by its own construction, it affords the necessary motion to the gases to prevent any noise at the exhaust. Moreover, particular attention is called to the fact that all 40 of the passages in the heater element are of precisely the same cross-section, so that absolutely no expansion of the gases can take place while passing through the heater element due to increased cross-area of these parts. This is a feature which appears to have been lost sight of in the construction 45 of heaters heretofore, so far as at present known, but the advantages of the construction have been amply demonstrated in practical use of heaters of the construction herein shown.

While particular constructions and arrangements of the heater are here illustrated and described, it is to be understood that the invention is not limited thereto, but that the form, construction and arrangement of parts may be varied widely within the scope of the appended claims.

60 What I claim is:

1. A heater for utilization of the exhaust gases of an internal-combustion engine comprising a heater element having a passage for the gases of substantially uniform cross-

sectional area throughout, the inlet and outlet ends of said passage being curved to produce a whirling motion to the gases both on entrance to and exit from said heater element, whereby the noise of exhaust from the heater is silenced. 65

2. A heater for utilization of the exhaust gases of an internal-combustion engine comprising a heating element proper having a sinuous passage of substantially uniform cross-sectional area throughout, the inlet and outlet ends of said passage being curved to produce a whirling motion to the gases in their passage through the heater element, and means at the exhaust port of said element to augment or increase the whirling motion of the gases whereby the noise of the exhaust from the gases of the heater element 70 is silenced. 75

3. A heater for utilization of the exhaust gases of an internal-combustion engine comprising a heater element proper having a plurality of parallel passages therein, alternate adjacent passages being connected at opposite ends of the heater, the end portion of the inlet passage of said heater element 80 being so formed as to impart a whirling motion to the gases upon entering the heater element, and the outlet passage having its end portion likewise formed to impart a whirling motion to the gases upon escape 85 from the heater element in order to silence the noise of exhaust of the gases from said heater element. 90

4. A heater for utilization of the exhaust gases of internal-combustion engines, comprising a heating element proper having a plurality of adjacent passages therein, alternate adjacent passages being in communication at opposite ends of the heater, a jet port 100 from the interior of the heater to the inlet 105 passage arranged tangentially to said passage for directing gas from said inlet into the exhaust passage to accelerate the passage of said gases through the heater.

5. A heater for utilization of the exhaust gases of internal-combustion engines, comprising a heating element proper having a plurality of adjacent passages therein, alternate adjacent passages being in communication at opposite ends of the heater, a port 110 from the interior of the heater into the outlet port of the heater and arranged tangentially to the wall of the said outlet port whereby gas may escape from the interior of the heater element into said outlet ports and 115 impart a whirling motion to the gases exhausting from said heater element to silence the noise of the exhaust. 120

6. A heater for utilization of the exhaust gases of internal-combustion engines, comprising a heating element proper having a plurality of adjacent passages therein, alternate adjacent passages being in communica- 125

tion at opposite ends of the heater, a port from the interior of the heater to the inlet passage arranged tangentially to said passage to direct gas from said inlet into the 5 exhaust passage to accelerate the exhaustion of said gas, and also a port into the outlet port of the heater arranged tangentially to the wall of said outlet port whereby gas may escape from the interior of the heater 10 element into said outlet passage and impart a whirling motion to the gases exhausting from said heater element to silence the noise of the exhaust.

7. A heater for utilization of the exhaust 15 gases of internal-combustion engines, comprising a heating element proper having a plurality of adjacent passages therein, alternate adjacent passages being in communication at opposite ends of the heater, a jet port

from the interior of the heater to the inlet 20 port for keeping the gases in motion through the heater passages toward the outlet port.

8. A heater for utilization of the exhaust gases of internal-combustion engines, comprising a heating element proper having a 25 plurality of adjacent passages therein, alternate adjacent passages being in communication at opposite ends of the heater, a jet port from the interior of the heater to the inlet passage arranged to direct a portion of the 30 incoming gas to displace the gases from which the heat has been extracted.

In testimony whereof I, the said PAUL J. CUBBISON, have hereunto set my hand.

PAUL J. CUBBISON.
